NONRIGID TOW TARGET

Walter B. Brewer, Jr., East Aurora, N. Y., assignor
to the United States of America as represented
by the Secretary of the Air Force

Application July 18, 1952, Serial No. 299,714

8 Claims. (Cl. 273—105.3)

1

This invention relates to tow targets for aerial gunnery and particularly to tow targets of the nonrigid type.

Tow targets for aerial gunnery are subject to rapid deterioration due to the violent oscillations of the flexible fabric or similar materials from which they are made.

To maintain these oscillations at as low a value as possible it is current practice to incorporate, in the design of the tow targets, appropriate aerodynamic stabilizing elements near the trailing end of the target thereby introducing a powerful factor toward suppression or elimination of the troublesome oscillations.

The invention has for an object the provision of means in the stabilizing elements which facilitate the storing and packaging of the target as well as assisting in the operation of launching through control of the rate at which the target is unfurled.

Other objects and advantages of the invention will become apparent from the following description and accompanying drawings in which like reference characters refer to like parts in the several figures.

Fig. 1 is a schematic view of apparatus embodying my invention shown with the tow cable reeled in and the target furled.

Fig. 2 is a view similar to Fig. 1 but with the tow cable payed out and the target partly unfurled.

Fig. 3 shows the flexible fabric target completely unwound and extended as it appears after the operation of the device.

Fig. 4 shows the outer or main torque tube upon which the flexible fabric target is rolled in readying the device for operation.

Fig. 5 shows an internally threaded cylinder which is constructed to contain a hydraulic fluid, there being means to force said fluid from said cylinder through a restricted outlet to retard unfurling of the target.

Fig. 6 shows a slotted torque tube sleeve which is adapted to transmit rotation from the torque tube to the internally threaded cylinder.

Fig. 7 shows an externally threaded piston arranged to remain nonrotative while engaging the internal threads of the internally threaded cylinder, whereby rotation of the said cylinder effects relative axial movement of the cylinder with respect to the piston.

Fig. 8 shows the drag element, which serves also as a container for the torque tube with the target wrapped around it.

Fig. 9 is a horizontal section through the drag element.

2

Fig. 10 shows one of the flexible loops with which the front of the target is provided.

Fig. 11 shows one of the flexible loops with which the rear end of the target is provided.

Fig. 12 is an assembly view of the parts which appear separately in Figs. 4, 5, 6 and 7.

Like reference characters refer to like parts throughout the several views.

The drag element 20, as shown in Fig. 8, comprises a framework consisting of vertically extending angle sections 22 supported by bulkheads 24. One of the four corners of the drag element 20 is open in the form of a slot 26 which extends substantially throughout the entire length of the drag element. Guide strips 28 with the lower portion of V form and the upper portion circular are spaced longitudinally of the drag element with the bottom of the V open and in register with the slot 26 of the drag element. At the open bottom of the V the corners are rounded. The dimensions of the guide strips 28 should be such that the target when closely rolled around the torque tube will enter through the guide strips quite freely. The purpose of this construction is important as will hereinafter appear.

The target, see Fig. 3, consists of a piece of woven fabric 30 which, for purposes of description, but not by way of limitation, may be about 6 feet wide by 30 feet long. The front end of the target is provided with reinforcing loops 32, Fig. 10, these loops being provided to receive the spreader bar 34 from which the bridle lines 36 extend and by which they are held spaced apart. The bridle lines converge (see Fig. 3) and meet in a common point at 38 where they are connected to the trailing end of the conventional tow cable 40 carried on a reel on the towing plane. A weight 42 on the bottom end of the spreader bar keeps the target in a vertical plane.

At the trailing end the target 30 is provided with reinforcing loops 44, Fig. 11, these loops being provided to receive a torque tube 46, Fig. 4, with the target 30 wrapped closely around it. This torque tube-and-target assembly may be entered longitudinally into the drag element 20 within the space surrounded by the guide strips 28, Fig. 9. The reason for the shape of the guide strips 28 will now be apparent, for when the target is rolled around the main torque tube and is in place in the drag element 20 within the guide strips 28, and is being pulled through the slot 26 to unreel it, the tube-and-target assembly bear against the V sides 29 of the guide strips thereby offering considerable resistance to being unrolled.

The main torque tube 46, both inside and out-

side, is of uniform diameter throughout its length. Within the main torque tube, intermediate its ends, there is a hollow internally threaded cylinder 48, Fig. 5, closed at one end and open at the other. An externally threaded piston 50, Fig. 7, on the end of a tubular shank 52, fits freely into the internal threads of the cylinder 48. A bearing collar 54 near the outer end of the shank 52 maintains concentricity between the shank 52 and the main torque tube 46. A block 56 at the extreme upper end of one of the vertical angle sections 22 of the drag element 20 supports a rod 58, the inner end of which extends into a slot 60 to prevent rotation of the shank 52 with respect to the drag element 20, whereby rotation of the cylinder 48 relative to the piston 50 moves the cylinder axially. A small hole 55 in the piston 50 permits a hydraulic fluid to escape slowly and thereby retard axial movement of the cylinder 48 as it is screwed over the piston 50.

The torque tube sleeve 62, Fig. 6, in the assembled device, lies between the main torque tube 46 and the cylinder 48. The torque tube sleeve 62 is slotted as at 64, two slots being 180 degrees apart, and the cylinder 48 has two pins 66 circumferentially spaced 180 degrees and registering with the slots 64. Two longitudinally spaced rivet holes 68 in the torque tube sleeve 62 register with two equally spaced holes in the main torque tube. In the complete assembly, rivets 70 extend through holes 68 in the torque tube sleeve and the corresponding holes in the main torque tube 46 to join these tubular members for unitary rotation. Rivets 70 should be finished flush with both the outside and the inside of the tube assembly. To facilitate entry of the pins 66 into the slots 64, the open ends of the slots are flared outwardly as at 71.

As finally assembled, see Fig. 12, the main torque tube 46 with the torque tube sleeve 62 now riveted therein is slipped over the internally threaded cylinder 48 with the pins 66 in the slots 64, the piston 50 is started into the cylinder 48, and the main torque tube 46 may be rotated, thereby rotating the sleeve 62 and the cylinder 48, the piston 50 remaining nonrotative because of the pin 58. The bearing collar 54 maintains concentricity of the outer end of the piston shank with the main torque tube 46. As thus assembled the torque tube sleeve 62 may neither rotate nor move axially with reference to the main torque tube 46; the cylinder 48 may move axially but may not rotate with reference to the main torque tube 46; and the piston 50, its shank 52 and bearing collar 54 may not move axially but may rotate with reference to the main torque tube 46.

In readying the device for operation, the main torque tube 46 with the sleeve 62 inserted and fastened by rivets 70 is slipped through the loops 44 on the trailing end of the target 30, then the target 30 is rolled around the outside of the tube 46. The tube 46 with the target rolled around it is then inserted endwise into the drag element 20 and within the bounds of the guide strips 28, several inches of the leading end of the target being unrolled and passed endwise through the slot 26 when the tube 46 is being inserted endwise into the drag element 20.

The spreader bar 34 is now attached to the leading end of the target, the bridle lines being permanently secured to the spreader bar by loops 32, Fig. 10. From the spreader bar 34, the bridle lines converge and are connected at 38 to the trailing end of the tow cable 40.

Next the pin 58 is withdrawn to allow the piston 50 with its shank 52, together with the cylinder 48, to be lifted out of the torque tube 46, and the cylinder 48 filled with a hydraulic fluid the piston 50 being screwed into place, and the subassembly 48-52 returned to its position in the main torque tube 46. As an alternative the piston 50 with its shank 52 may be removed without withdrawing the cylinder 48, the cylinder in that case being serviced in situ. The pin 58 is now returned to the position shown.

In the schematic view, Fig. 1, a tow plane 72 is equipped with the conventional cable reel 74 upon which the tow cable 40 is substantially fully rolled, the trailing end of the tow cable 40 being at 38. Bridle lines 36 have their leading ends joined at 38 to the trailing end of the tow cable 40, and diverge and are joined in spaced relation to the spreader bar 34. The leading end of the target 30 is joined to the spreader bar 34 by loops 32.

Within the drag element 20 and within the bounds of the guide strip 28, the target 30 is fully rolled except for several inches which protrude as at 76 from the slot 26 of the drag element 20.

The device may now be launched by paying out tow cable 40 from the reel 74, the hydraulic system in the meantime operating automatically to control the unfurling of the target 30.

Fig. 2 shows the device with the tow cable extended and the target partly unfurled.

Having described an embodiment of my invention, I claim:

1. A nonrigid tow target comprising a rotatable rigid torque tube, a flexible fabric target closely rolled over the outside of said rigid torque tube, and resistance means including a cylinder closed at one end and a dash pot piston therein within said tube responsive to unrolling of said target from off the outside of said tube to move axially relatively toward each other to provide resistance to rotation of said tube to retard unrolling of said target.

2. A tow target comprising an elongated drag element, a torque tube positioned longitudinally in said drag element and rotatable with reference thereto, a tow target wrapped snugly around said torque tube and adapted to be unrolled to rotate said torque tube, rotation retarding means within said torque tube including an internally threaded cylinder and an externally threaded piston therein responsive to rotation of said torque tube to move relatively axially toward each other, and a resisting means within the cylinder opposing said axial movement.

3. A tow target comprising a drag element, a torque tube positioned vertically in said drag element and rotatable therein with reference thereto, a flexible fabric target secured to said torque tube and closely rolled around said torque tube whereby unrolling said target rotates said torque tube with reference to said drag element, and resisting means within said torque tube movable axially with respect thereto by unrolling of said target to rotate said torque tube.

4. A tow target comprising a drag element, a torque tube positioned vertically in said drag element and rotatable therein with respect thereto, a flexible fabric target secured to said torque tube and closely rolled therearound, whereby pulling on the outer end of said fabric target to unroll said target rotates said torque tube, a sleeve within said torque tube constructed to rotate therewith, a cylinder within said sleeve ro-

75

tatable thereby and axially movable therein, a piston in said torque tube fixed against rotation and axial movement with reference to said drag element, and means responsive to rotation of said torque tube to move said cylinder axially with respect to said piston.

5. A tow target comprising a drag element, a torque tube positioned vertically in said drag element and rotatable therein with respect thereto, a flexible fabric target secured to said torque tube and closely rolled therearound, whereby pulling on the outer end of said fabric target to unroll said target rotates said torque tube, a sleeve within said torque tube constructed to rotate therewith and fixed against axial movement therein, an internally threaded cylinder within said sleeve and rotatable thereby and axially movable therein, an externally threaded piston within said internally threaded cylinder fixed against rotation and axial movement with respect to said drag element, and means to release said piston to permit rotation thereof.

6. A tow target comprising an elongated hollow drag element slotted throughout its length, a torque tube of substantially less outside diameter than the inside diameter of said drag element positioned longitudinally in said drag element, guide strips carried by said drag element of substantially greater inside diameter than the outside diameter of said torque tube and slotted to correspond to said drag element, a flexible fabric target having one end secured to said torque tube and closely rolled therearound and the other end extended outwardly through the slots of the drag element and of the guide strips whereby pulling on the extending end of said target rotates said torque tube, a sleeve within said torque tube adapted to rotate therewith and fixed against axial movement therein, an internally threaded cylinder within said sleeve rotatable thereby and axially movable therein, and an externally threaded piston threadably received in said internally threaded cylinder and fixed against rotation and axial movement during rotation and axial movement of said cylinder during rotation of said torque tube by unrolling of said flexible fabric target from the said torque tube.

7. A tow target comprising an elongated hollow drag element of square transverse section 50 with one corner slotted throughout its length,

guide strips of V-shaped contour in one corner of the drag element with the sides of the V lying along the sides of the drag element and the point of the V slotted and in alignment with the slot of the drag element, a torque tube extending longitudinally within the drag element and within the confines of the guide strips, a flexible fabric target having one end secured to said torque tube and closely rolled therearound and the other end extended outwardly through the said slots whereby pulling on the extending end of said target first pulls said target against the sides of the V then rotates the said target against the frictional resistance between the rolled target and the sides of the V, whereby the unrolling of the target is retarded.

8. A tow target comprising an elongated hollow framework of square transverse section with one corner slotted throughout its length, guide strips of V-shaped contour in one corner of the drag element with the sides of the V lying along the sides of the drag element, and the point of the V slotted and in alignment with the slot of the drag element, a torque tube extending longitudinally within the drag element and within the confines of the guide strips, a flexible fabric target having one end secured to said torque tube and closely rolled therearound, and the other end extended outwardly through the said slots, whereby pulling on the extended end of said target first pulls said target against the sides of the V, then rotates the said target against the frictional resistance between the rolled target and the sides of the V whereby the unrolling of the target is retarded, and hydraulic leakage means within the torque tube operative by rotation of the torque tube to control said hydraulic leakage means to further retard unrolling of said target.
